M. KIRNBAUER.
FRUIT AND VEGETABLE CUTTER.
APPLICATION FILED JAN. 14, 1922.

1,415,449.

Patented May 9, 1922.

UNITED STATES PATENT OFFICE.

MICHAEL KIRNBAUER, OF FOREST PARK, ILLINOIS.

FRUIT AND VEGETABLE CUTTER.

1,415,449.

Specification of Letters Patent. Patented May 9, 1922.

Application filed January 14, 1922. Serial No. 529,108.

To all whom it may concern:

Be it known that I, MICHAEL KIRNBAUER, a former subject of the Austria-Hungary Empire, (who has declared his intention of 5 becoming a citizen of the United States of America,) and a resident of Forest Park, in the county of Cook and State of Illinois, have invented certain new and useful Improvements in Fruit and Vegetable Cutters, 10 of which the following is a specification.

This invention relates to that type of fruit and vegetable slicing implements in which the cutter blade is mounted in transverse relation on a flat work board or trough, along 15 which the material to be sliced is reciprocated by hand and past the cutter blade to attain the desired slicing result. And this improvement has for its objects:

To provide a simple and efficient structural formation and association of parts whereby the cutter blade can be adjusted in an even and uniform manner in relation to the surface of the work board to attain a desired thickness in the slicing operation.

To provide a reversible form of slicing implement adapted to attain either a slicing or a shredding of the material operated on, and in which a simple and efficient arrangement of the shredding cutter is provided, 25 all as will hereinafter more fully appear.

In the accompanying drawing:—

Fig. 1, is a perspective view of a slicing implement embodying the present invention.

Fig. 2, is a detail sectional plan view, with parts removed to show the adjusting means of the slicing cutter.

Fig. 3, is a detail longitudinal section on line 3—3, Fig. 2.

Fig. 4, is a similar view on line 4—4, Fig. 2.

Fig. 5, is a detail plan view, with parts removed, showing the construction of the shredding cutter.

Fig. 6, is a detail longitudinal section on line 6—6, Fig. 5.

Like reference numerals indicate like parts in the several views.

Referring to the drawing, 1 designates 50 the work plate or base of the implement of a flat oblong form and provided at the sides of its respective faces with guide ledges or strips 2 as shown.

3 designates bracket plates set in the side

portions of the work plate 1, beneath the strips 2, with their flanges forming bearings for the revoluble carrying shaft of the slicer blade now to be described.

4 designates the slicer blade of a flat rectangular form arranged transversely between 60 the bracket plates 3 aforesaid, with its rear or butt end fixedly attached to a transverse carrying shaft or rod 5 journalled in orifices in said bracket plates.

6 designates an angularly arranged arm 65 or extension on one end of the shaft 5 aforesaid, formed at its outer end with gear teeth adapted for operative engagement with the hereinafter described operating worm or screw shaft, as shown in Fig. 4, to attain 70 a pivotal adjustment of the slicer blade 4 carried by said shaft 5.

7 designates a bridge plate secured to one of the bracket plates 3 and formed with a journal orifice in spaced and alined relation 75 to a similar journal orifice in said bracket plate.

8 designates a revoluble shaft journalled in the orifices of the bridge and bracket plates above described and formed with stop 80 shoulders for engagement with said plates to hold the shaft against endwise movement after an assembly of the parts.

9 designates a thumb nut or other like operating means on the outer end of the 85 shaft 8 for the convenient turning of the same by hand in effecting an adjustment of the slicing cutter and its carrying shaft 5 aforesaid.

10 designates a worm or screw formed on 90 the intermediate portion of the shaft 8 and having operative engagement with the gear teeth on the outer end of the arm or extension 6 aforesaid. With such construction of the parts an even and uniform adjustment 95 of the whole length of the slicer blade 4 to and from the surface of the work board 1 can be effected when a change in the thickness of the cuts is to be made by the application.

11 designates a series of cutter strips inserted in the material of the work board 1 in transverse spaced relation to each other, and preferably in oblique relation to the surface of said work board.

12 designates outlet orifices extending through the work board 1 beneath the above described slicing and shredding cutters, for

100

105

the outlet of the sliced or shredded material as the same is produced in a continued operation of the implement.

15 designates a hand opening in the end 5 of the work board 1 for convenient holding of the implement in proper position during the practical use of the same.

Having thus fully described my invention, what I claim as new and desire to secure by 10 Letters Patent, is:—

1. In a slicing implement, a flat work board, a cutter blade arranged transversely of the same, a shaft journalled transversely on said work board and having a lateral arm 15 at one end, the butt of the cutter blade being secured to said shaft, and means for imparting a turning movement to said arm and its associated parts, the same comprising gear teeth on the outer end of the lateral

arm, and a worm shaft journalled in the 20 work board and having operative engagement with the gear teeth of said arm.

2. In a slicing implement, a flat work board having side guide strips, bracket plates secured beneath said guide strips, a 25 transverse shaft journalled in said bracket plates and having a lateral arm at one end, a cutter blade carried by said shaft, a bridge plate attached to one of said bracket plates, a worm shaft journalled in said bridge and 30 bracket plates and having an operating means on its outer end, the lateral arm aforesaid having gear teeth on its outer end for operative engagement with the worm shaft aforesaid. 35

Signed at Chicago, Illinois, this 11th day of January, 1922.

MICHAEL KIRNBAUER.
